POWDER SPRAYER

Henry J. Berenson, St. Paul, Minn., assignor to
 Mueller Can & Tube Co., St. Paul, Minn., a
 corporation of Minnesota

Application September 18, 1940, Serial No. 357,193

3 Claims. (Cl. 221—61)

My invention relates to powder sprayers and has for an object to provide an extremely practical construction for the purpose.

Another object of the invention resides in providing a powder sprayer which can be constructed at an economical cost.

A still further object of the invention resides in providing a powder sprayer which may be used to spray powder regardless of the position in which the sprayer is held.

An object of the invention resides in providing a powder sprayer having an air duct and so constructed that the powder is caused to enter the air duct by means of gravity, suction, and air pressure.

An object of the invention resides in constructing the sprayer with a tubular receptacle having a circumferential wall and end walls connected therewith and provided with an air duct disposed eccentrically relative to the circumferential wall.

Another object of the invention resides in forming said duct by means of a partition having flanges thereon secured to the circumferential wall of the receptacle.

A still further object of the invention resides in providing the duct with openings at both ends thereof communicating with the receptacle at the two ends thereof and in proximity to the end walls of the receptacle.

A feature of the invention resides in providing in one end wall a discharge outlet communicating with the air duct and in providing at the other end an air inlet communicating with the air duct.

An object of the invention resides in arranging the opening in the air duct adjacent the air inlet laterally of the air inlet to cause a suction to be induced in said opening whereby the powder in the receptacle is drawn into said duct through said opening by means of suction.

Another object of the invention resides in constructing said discharge outlet of a cross section considerably less than the cross section of the opening in the duct adjacent thereto to cause a pressure to build up in the discharge end of the duct, forcing air into the compartment containing the powder and causing the powder to enter the duct through the other opening.

Another object of the invention resides in providing a tubular member having a head at one end and in which the receptacle is received, said receptacle forming in conjunction with said tubular member a piston for forcing the air through the air inlet and into the air duct.

A feature of the invention resides in providing a valve in said head and also in the specific construction of said valve.

Other objects of the invention reside in the novel combination and arrangement of parts and in the details of construction hereinafter illustrated and/or described.

In the drawings:

Fig. 1 is a plan view of a powder sprayer illustrating an embodiment of my invention.

Fig. 2 is a longitudinal elevational sectional view taken on line 2—2 of Fig. 1.

Fig. 3 is a view similar to Fig. 2 showing the parts in altered position.

Fig. 4 is a view similar to Fig. 3 showing the sprayer in action when arranged at an upwardly inclining angle.

Fig. 5 is a view similar to Fig. 4 showing the sprayer in action when arranged at a downwardly inclining angle.

Fig. 6 is a cross sectional view taken on line 6—6 of Fig. 2.

Fig. 7 is a cross sectional view taken on line 7—7 of Fig. 2.

Fig. 8 is a fragmentary elevational sectional view taken on line 8—8 of Fig. 6.

My invention comprises a receptacle 10 which includes a body portion 11 and a removable cap 12. The receptacle 10 has associated with it a

tubular member 13 which operates in conjunction with the said receptacle to form an air pump. These parts will now be described in detail.

The body portion 11 of the receptacle 10 includes a cylindrical or circumferential wall 14 which may be constructed from a tube of paper or some other similar material. This circumferential wall has attached to one end thereof an end wall 15, preferably formed of sheet metal, which is provided with a flange 16 crimped about the lower end of the wall 14 whereby the same is attached thereto. The other end of the circumferential wall 14 is open and is adapted to be closed by the cap 12.

The cap 12 is constructed with a tubular portion 17, also constructed from a tube of paper or some similar material which is provided with an end wall 18 formed of sheet metal having a flange 19 crimped about the end of said tubular portion and thus securing said end wall thereto. The circumferential wall 14 of the body portion 11 is adapted to telescope within the tubular portion 17 and fits closely within the same, so that, when the cap 12 is applied to the body portion

11, the receptacle 10 becomes closed at its ends through the end walls 15 and 18.

The cap 12 is employed for the purpose of giving access to the interior of the receptacle for filling the same with powder. If desired, the said cap may be dispensed with and the end wall 18 secured to the end of the circumferential wall 14 and other means formed in the end wall 18 for filling the receptacle.

The tubular member 13 is constructed from a tube 21 of paper or some other similar material which is provided at its end with a head 22. This head is constructed from sheet metal and is formed with a flange 23, similar to the flange 16, which is crimped about the lower end of the tube 21. The head 22 is similar in construction to the end wall 15 of the receptacle 10. The circumferential wall 14 of the container 11 is adapted to fit snugly within the interior of the tube 21. To cause a tight fit between the wall 14 and tube 21, the flange 16 is caused to lie flush with, or inwardly of the outer surface of the wall 14. By means of this construction an air pump is formed, the receptacle 10 serving as a piston and the tubular member 13 serving as a cylinder. It will thus become evident that upon relative movement between the receptacle 10 and tubular member 13, the air between the head 22 and the end wall 15 will be compressed.

Within the interior of the receptacle 10 is provided a partition 24 constructed of paper or some other similar material which is formed with two flanges 25. The width of the partition 24 is less than the internal diameter of the circumferential wall 14. The two flanges 25 are glued or otherwise attached to the circumferential wall 14, as shown in Fig. 6. By means of this construction a compartment 26 is formed on one side of the said partition, and a duct 27 is formed on the other side of said partition. In Fig. 6 it will be noted that the cross sectional area of the duct 27 is considerably less than the cross sectional area of the compartment 26. The partition 24 falls short of the end walls 15 and 18 of the receptacle 10 to form two openings 28 and 29, in the portion, which bring the compartment 26 at its ends into communication with the duct 27 at its ends. The powder to be dispensed is kept in the compartment 26 and may pass through the openings 28 and 29 into the duct 27.

In the head 22 of the tubular member 13 is formed two holes 31 and 32 which are spaced from one another. Extending across these holes is a flapper valve 33 constructed of paper, which valve is held in position intermediate the ends thereof by means of two tongues 34 struck up from the metal of the head 22 and overlying the said valve, intermediate the ends thereof. By means of this construction the outermost portions 35 of the valve may swing upwardly from the head 22, as shown in Fig. 3, to allow air to pass through the holes 31 and 32 and into the chamber 36 formed within the tube 13 and between the head 22 and the end wall 15. When the tubular member 13 is moved toward the head 15 the air within the chamber 36 is compressed and the valve member 33 closed.

In the end wall 15 is provided a hole 37 which forms an air inlet communicating with the duct 27. This air inlet is covered with a screen 38 formed of fabric or any other suitable material, which screen overlies the entire surface of the end wall 15 and is held in place under the flange 16. In the end wall 18 is formed a cup-shaped depression 41 which is constructed at the center

of the same with a small hole 42 which serves as a discharge outlet. This hole is situated opposite the duct 27. It will readily be comprehended that, when air is compressed in the chamber 36 the same travels along the duct 27 and picks up whatever powder is in the duct and discharges the same through the discharge outlet 42.

The operation of the invention is as follows: When the sprayer is positioned, as shown in Fig. 4, the powder extends down toward the end wall 15 and overlies the opening 29. A certain amount of the powder passes through said opening and into the duct 27 by the action of gravity. When the tubular member 13 is drawn outwardly the valve 33 opens as shown in Fig. 3 permitting air to enter the chamber 36. As the said tubular member is moved toward the receptacle 10 the air chamber 36 becomes compressed, the valve 33 closes and the air is forced through the screen 38 along the duct 27 and out through the discharge outlet 42. This action creates a current of air in duct 27 which picks up the powder entering the said duct and due to the size of the discharge opening 42 and the depression 41 formed in end wall 18 the powder is sprayed in the form of a cloud of dust upon leaving the sprayer. Due to the use of the screen 38 the powder does not drop into the chamber 36 but is confined to the duct 27. The valve 33 being constructed of paper the resistance to the opening of the same is so slight that practically no suction is produced in the duct 27 when the tubular member 13 is withdrawn. For this reason the powder remains in the compartment 26 and in the duct 27. While the air is traveling along the duct 27, the velocity of the current of air flowing through the air inlet 37 and past the opening 29 induces a suction at said opening which draws the powder from the compartment 26 and into the duct 27. At the same time, due to the indentation 41 and due to the relatively small area of the discharge outlet 42 compared to the area of the opening 29 a pressure is created in the upper portion of the passageway 27 which creates a pressure in the upper part of the compartment 26. This pressure assists in forcing the powder in the compartment 26 toward the opening 29 from which it may enter into the duct 27. When the device is held in the position shown in Fig. 5 the powder moves toward the discharge end of the receptacle. The powder may then flow out through the opening 28 and into the duct 27. The air flowing through the duct produces the same effect and causes a cloud of dust to leave the sprayer from the nozzle 42. While the pressure created in the duct 27 tends to force the powder back through the opening 28, yet it is to be remembered that this pressure is relieved during the return stroke of the tubular member 13 allowing another charge of powder to enter the duct 27 by gravity. It will thus become apparent that the device will operate whether inclined downwardly or inclined upwardly. When the device is positioned vertically the results are the same as produced when inclined in the manner shown in Fig. 4. If the device is turned so that the duct 27 is uppermost, the device still functions. When so arranged and inclined as shown in Fig. 4, the lowermost opening still remains closed and powder may enter into the duct 27 by gravity. In addition, the pressure and suction previously referred to augment this action. The same is true when the sprayer is arranged with the duct 27 uppermost

and disposed in the position shown in Fig. 5. Should the sprayer be held horizontally with the duct 27 uppermost, both openings 28 and 29 would be uncovered. This would permit the air to circulate freely through the part of the compartment 26 adjacent the partition 24, which would be occasioned by the pressure of the air at the opening 28 and the suction at the opening 29. The air, in passing over the powder in the compartment 26, would in such case pick up some of it and a certain amount of powder would be discharged through the orifice 22. The amount of the powder so discharged would, of course, be increased in accordance with the violence with which the tubular member 13 was manipulated. It will thus be readily comprehended that the device will operate to spray powder in any position in which the same may be ordinarily held for the purpose.

The advantages of my invention are manifest. The sprayer is extremely simple and has no complicated parts to get out of order. The device may be easily constructed and with machinery now available for the purpose. The sprayer operates at any position in which the same may be conveniently held for spraying purposes so that the operator does not have to hold the same in any particular manner. My invention can be made to discharge the entire contents thereof so that waste does not occur. My improved sprayer may be made extremely attractive in appearance and resembles an ordinary container.

Changes in the specific form of my invention, as herein disclosed, may be made within the scope of what is claimed without departing from the spirit of my invention.

Having described my invention, what I claim as new and desire to protect by Letters Patent is:

1. A powder sprayer comprising a receptacle having end walls and a lateral wall structure, a partition within said receptacle extending between the end walls thereof and dividing the receptacle into an air duct and a compartment for the reception of powder, flanges formed on said partition and secured to the lateral wall structure of the receptacle for holding the partition in place, said partition being spaced from the end walls of the receptacle to form openings therebetween extending throughout the width of said partition for bringing said compartment into communication with said duct, a discharge outlet in one of said end walls communicating with said duct and an air inlet in the other of said

end walls communicating with said duct and opposite the end thereof.

2. A powder sprayer comprising a receptacle having end walls, a member within said receptacle providing an air duct extending from one end wall thereof to the other, said member having a laterally extending opening therein at one end, the end wall of said receptacle adjacent said opening having a discharge outlet therein, said member having another opening therein at its opposite end through which the powder may enter the duct, the other end wall of the receptacle having an inlet communicating with said duct through which air may be forced into the duct, said discharge outlet being sufficiently small to create a pressure in the duct at the discharge end of the duct forcing air into the receptacle at the upper end and through the opening in the member adjacent the discharge end of the duct,
- 15 the opening in the end wall of the receptacle through which air enters the duct being sufficiently small to produce an air current past said inlet opening in the member and create a suction at said opening, the action of the air passing
- 20 through the duct causing the entry of powder into the duct through the opening in the member adjacent the inlet opening and resulting in the spraying of the powder and air on leaving the discharge outlet.
- 25 3. A powder sprayer comprising a receptacle having end walls, a member within said receptacle providing an air duct extending from one end wall thereof to the other, said member having a laterally extending opening therein at one end,
- 30 35 the end wall of said receptacle adjacent said opening having an inlet causing the air entering said duct to travel at right angles to said opening and inducing a suction through said opening tending to draw the powder into the duct,
- 40 45 50 through said opening, the other end of said receptacle having a discharge outlet therein communicating with said duct, said member having another opening at its other end in proximity to said discharge outlet, said discharge outlet being of sufficiently small cross sectional area to create pressure within said duct forcing air into the receptacle through the opening in said member adjacent the discharge outlet, the action of the air passing through the duct causing the entry of powder into the duct through the opening in said member adjacent the inlet opening and resulting in the spraying of the powder and air on leaving the discharge outlet.

HENRY J. BERENSON.
